Attorney

UNITED STATES PATENT OFFICE.

RALPH C. RENIHAN, OF TROY, NEW YORK, ASSIGNOR TO VAN ZANDT, JACOBS & CO.,
OF TROY, NEW YORK, A CORPORATION OF NEW YORK.

SOFT FOLD-COLLAR.

1,223,521.

Specification of Letters Patent. Patented Apr. 24, 1917.

Application filed December 1, 1916. Serial No. 134,445.

To all whom it may concern:

Be it known that I, RALPH C. RENIHAN, a citizen of the United States, residing at Troy, county of Rensselaer and State of New York, have invented certain new and useful Improvements in Soft Fold-Collars, of which the following is a specification.

Reference may be had to the accompanying drawings and the reference characters 10 marked thereon, which form a part of this specification. Similar characters refer to similar parts in the several figures therein.

The principal object of the invention is to support in proper relative relation, the band 15 and the folded-over top of a soft fold-collar.

Other objects will appear in connection with the following description.

Figure 1 of the drawings is a plan view of a soft fold-collar laid out flat, and provided with stiffeners for the band and the top in accordance with my invention.

Fig. 2 is a cross-section of the same taken on the broken line 2—2 in Fig. 1, showing the collar folded.

Fig. 3 is a view in perspective of one of the bifurcated stiffeners, whereby the band and the folded-over top are held in proper relative position.

Referring to the drawings wherein the invention is shown in preferred form, 1 is the band, and 2 is the top of a soft fold-collar, each being made of a plurality of plies of fabric in the usual manner.

The top may be connected with the band 35 in any known manner, as by inserting the top in the band as shown in the drawings.

In carrying out my invention, I provide a stiffener-receiving pocket in the band, opening at 3, toward the top, and a similar 40 stiffener-receiving pocket in the top, opening at 4, toward the band.

The pocket thus formed in the top is opposite the pocket in the band, said pockets being adapted to receive the respective legs 45 or branches of a bifurcated stiffener 5.

The pockets may be thus formed in the band and the top by forming buttonholed slits at 3 and 4, respectively in the inner plies

of the band, and 1 of the top, permitting the legs or branches of the stiffeners to enter 50 between the plies of the respective members of the collar.

While I have shown the pockets formed by buttonholed slits, I wish it to be understood that the band and the top can be provided in any known manner with suitable 55 pockets or other means adapted to be engaged by the respective legs or branches of the bifurcated stiffener.

The stiffener 5, may be made of any suitable material as celluloid, bristol-board or the like, and may be of any desired width. For use, the stiffener is folded at 6, along a transverse line to substantially hairpin-shape, and its legs or branches are preferably proportioned in length respectively to the height of the top and of the band of the collar.

The fold 6, may be formed in the stiffener either before or after it is inserted in the 70 pockets in the top and band of the collar.

I have shown the collar provided in the manner described with two stiffeners 5; but any desired number of such stiffeners may be employed. The stiffeners can be readily removed when it is desired to launder the 75 collar.

By the use of my invention I am able to not only stiffen and reinforce both the band and the folded-over top of the collar, but 80 I am also able to hold the band and the top in proper relative position, thus preventing disarrangement of the collar, and adding to its attractive appearance in use.

What I claim as new and desire to secure 85 by Letters Patent is—

1. The combination with a fold-collar having a band and a folded-over top; of a bifurcated stiffener one branch of which engages the band and the other branch the 90 folded-over top of the collar.

2. The combination with a collar comprising a band and a folded-over top each provided with a stiffener-receiving pocket opening toward the fold in the top, said 95 pockets being disposed opposite each other;

of a folded stiffener having its legs inserted in the respective pockets in the band and the top.

3. A fold-collar comprising a band and a 5 folded-over top, said band being provided with a stiffener-receiving pocket opening toward the folded-over top, and said folded-over top being provided with a stiffener-

receiving pocket opening toward the band opposite said pocket in the band, said pockets being adapted to receive the respective branches of a bifurcated stiffener.

In testimony whereof, I have hereunto set my hand this 22nd day of November, 1916.

RALPH C. RENIHAN.
